(57) CLAIM

The ornamental design for a golf club head, as shown.

DESCRIPTION

FIG. 1 is a front elevation view of the invention illustrating our design;

FIG. 2 is a rear elevation view thereof;

FIG. 3 is a top elevation view thereof;

FIG. 4 is a bottom elevation view thereof;

FIG. 5 is a left side elevation view thereof;

FIG. 6 is a right side elevation view thereof; and,

FIG. 7 is a sectional view taken along line 7—7 of FIG. 2.
